US0D1065065S

(12) **United States Design Patent** (10) Patent No.: **US D1,065,065 S**
(45) Date of Patent: ** Mar. 4, 2025

(54) **WIRELESS CHARGER**

(71) Applicant: **Shenzhen Xiaojiu Technology Co., Ltd.**, Shenzhen (CN)

(72) Inventors: **Biaolong Zhong**, Shaoyang (CN); **Chunlin Chen**, Shaoyang (CN); **Guihai Ruan**, Shaoyang (CN)

(73) Assignee: **Shenzhen Xiaojiu Technology Co., Ltd.**, Shenzhen (CN)

(**) Term: **15 Years**

(21) Appl. No.: **29/876,701**

(22) Filed: **May 26, 2023**

(30) **Foreign Application Priority Data**

Jan. 6, 2023 (CN) 202330006453.5

(57) **CLAIM**

The ornamental design for a wireless charger, as shown and described.

DESCRIPTION

FIG. 1 is a front perspective view of a wireless charger, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the wireless charger, which form no part of the claimed design.

1 Claim, 8 Drawing Sheets
